(57) **CLAIM**

(21) Appl. No.: **29/143,008**

The ornamental design for a funny bunny bottle, as shown and described.

(22) Filed: **Jun. 7, 2001**

DESCRIPTION

(51) LOC (7) Cl. **09-01**

FIG. 1 is an orthogonal view of the invention;

(52) U.S. Cl. **D9/318**

FIG. 2 is a front view of the invention;

(58) Field of Search D9/310, 318, 307;
D21/655; 206/457; 215/381-383, 400

FIG. 3 is a rear view of the invention;

(56) **References Cited**

FIG. 4 is a right side view of the invention;

U.S. PATENT DOCUMENTS

FIG. 5 is a left side view of the invention;

D167,375 S * 7/1952 Rioux D21/655

FIG. 6 is a top view of the invention; and,

D236,439 S * 8/1975 Gottsegen .... D21/655 X

FIG. 7 is a bottom view of the invention.

D302,940 S * 8/1989 Ferrero D9/318

The broken lines are for illustrative purposes only and form no part of the claimed design.
